UNITED STATES PATENT OFFICE.

FRANK CHAPMAN, OF BROOKLYN, NEW YORK, ASSIGNOR OF ONE-HALF TO HARRY G. FISHER, OF BROOKLYN, NEW YORK.

PORTABLE CLOTHES DRIER.

Application filed December 5, 1923. Serial No. 678,746.

To all whom it may concern:

Be it known that I, FRANK CHAPMAN, a citizen of the United States of America, residing at Brooklyn, in the county of Kings 5 and State of New York, have invented certain new and useful Improvements in Portable Clothes Driers, of which the following is a specification.

This invention relates to a portable clothes 10 drier designed particularly to be used in a window or like opening and adapted when not in use to be folded into small compact form for storage without separation of any of the parts.

15 The clothes drier of this invention is designed more particularly for use in connection with small articles and is constructed to be readily and conveniently clamped in position between the outer and intermediate 20 beads of a window frame, the supporting members directly receiving the clothes or other articles, being conveniently flexible to permit a compact arrangement of the parts when the device is not in use.

25 The invention is illustrated in the accompanying drawings, in which:

Fig. 1 is a perspective view illustrating the drier in position in a window frame ready for use.

30 Fig. 2 is a perspective view of the drier partly collapsed, indicating the manner in which the parts are to be arranged when folding for storage.

Fig. 3 is a perspective view of the device 35 folded, the ropes being omitted.

Fig. 4 is a detail showing the mounting of the arms.

Fig. 5 is a detail showing the mounting of the brace bars.

40 The improved drier comprises duplicate side members, including uprights 1 of a width to fit between the outer or inner and intermediate beads 2 and 3 of an ordinary window frame 4, the height of the uprights 45 being preferably less than the height of the lower sash. These side members also include supporting arms 5, which are hingedly connected at 6 to the lower ends of the uprights, there being preferably provided metallic strips 7 adjacent the hinge connection 50 which may be utilized to assist in holding the supporting arms in contact with the uprights, to avoid strain on the hinge connections and assist in holding the arms in spread

relation against the weight of the clothes on 55 the drier. The respective supporting arms are connected by flexible article receiving lines 8, or a single line preferably substantial cord or thin rope, these lines being terminally passed through openings in the supporting arms 5. As preferred, the clothes line is in the form of a single line, terminally secured at one end to the arm and laced 60 between the respective arms, through openings therein, with the final end of such length as to permit adjustment between the arm in accommodating different widths of drier for different widths of window.

Connected to the respective uprights 70 slightly below their mid-lengths are brace bars 9, of appropriate lengths and formed for interconnection, as for example, through the medium of slot 10 formed in one of said bars 9 and a thumb screw 11 carried by the other brace bar and extending through the slot. The clothes supporting frame including the side arms 5 and the lines 8 are limited in their opening movement by flexible ties 12 connected to the uprights and to the free ends of the supporting arms, these ties 75 limiting the drier frame to a substantially horizontal position when in use. The metallic strips 7 are of angle form with the short arm secured to the bottom of the uprights 1, and the long arm spaced from the 80 walls of the uprights, to provide for the movement of the supporting arms 5 between the long arms of the strips and the uprights, when the supporting arms are turned into operative positions.

85 In applying the device for use, the uprights 1 are positioned in the window frame between the outer and intermediate beads below the upper sash, this arrangement moving the brace bars 9 into a substantially horizontal position and extending them to form an effective brace between the uprights, which when the thumb screw 11 is tightened, serves to secure the uprights in fixed position in the window frame against movement under ordinary strains. The upper ends of the uprights are provided with metal strips 13 having serrations or teeth 14, to bite into the wood of the window frame 90 to assist in holding the drier. The supporting frame including the arms 5 and lines 8 are lowered into a substantially horizontal position, or to the limit permitted by 100 105

the ties 12, the supporting arms in this position preferably resting upon and being supported by the sill of the window, as shown in Fig. 1. The lines 8 are thus disposed beyond the window structure and small articles may be readily hung on such lines 8 for drying. The uprights are provided with hooks 15 into which the ties 12 may be temporarily looped to assist in holding the arms in angular position when first setting the device. These hooks also serve to shorten the operative length of the ties, as desired, to hold the arms at any final angle to the horizontal, as may be desirable in use.

Furthermore, it is obvious that the drier as a whole may be completely reversed in position and the supporting frame extended within the room, to permit drying of articles in rainy weather or the like.

When the device is not desired for use, the thumb screw 11 is loosened and the brace bars turned upwardly, permitting the uprights 1 and supporting arms 5 to be moved into close contact and the lines 8 and ties 12 wrapped around the parts or interfolded therewith. A compact structure is thus provided for which occupies little room in storage.

30 The rigid parts of the structure may be conveniently constructed of wood, light metal, or other appropriate material, and it is to be particularly noted that either in extending for use or folding for storage, no 35 separation of any parts is necessary, the device remaining intact and requiring substantially but a single operation in either arranging for use or collapsing.

Claims:

40 1. A portable clothes drier, comprising duplicate side members, each including an upright adapted to be placed in contact with a window or door frame and a supporting arm hinged thereto, flexible lines connecting the supporting arms, and intercon-

nected brace bars extending from the uprights adapted to hold said uprights in binding and supporting contact with the window or door frame.

2. A portable clothes drier, comprising 50 duplicate side members, a supporting arm hinged adjacent one end of each of said members, interconnected brace bars arranged between the members, and means secured to the members and having upright 55 portions spaced from the members in advance of the hinged connection of the supporting arm to limit the hinged movement of the supporting arm in one direction and prevent lateral play of such arm when in 60 operative position.

3. A portable clothes drier, comprising uprights to be arranged between adjacent beads of a window frame, a brace bar extending from the inner side of each upright, 65 means for rigidly connecting the brace bars to hold the uprights in binding position in the window frame, a supporting arm hingedly connected to the lower end of each upright, flexible article supporting lines extending between and connected to the supporting arms, and flexible ties connecting the upper ends of the uprights and supporting arms.

4. A portable clothes drier, comprising 75 duplicate side members, each including an upright and a supporting arm hinged thereto, flexible lines connecting the supporting arms, flexible tie members connecting the outer ends of the arms and the uprights to 80 thereby normally hold the arms in a substantially horizontal position, and hooks on the uprights to shorten the effective lengths of the ties at will to thereby hold the arms in a substantially inclined position, and interconnected brace bars extending from the uprights to force the latter into binding contact with a window or door frame.

In testimony whereof I affix my signature.

FRANK CHAPMAN [L. s.]
